UNITED STATES PATENT OFFICE

WALTER D. TEAGUE, OF FOREST HILLS, NEW YORK, ASSIGNOR TO THOMAS A. EDISON, INCORPORATED, OF WEST ORANGE, NEW JERSEY, A CORPORATION OF NEW JERSEY

DESIGN FOR A CALCULATING MACHINE CASING OR SIMILAR ARTICLE

Application filed January 19, 1932. Serial No. 42,538. Term of patent 14 years.

To all whom it may concern:

Be it known that I, WALTER D. TEAGUE, a citizen of the United States and a resident of Forest Hills, L. I., in the county of Queens and State of New York, have invented a new, original, and ornamental Design for Calculating Machine Casings or Similar Articles, of which the following is a specification, reference being had to the accompanying drawings, forming a part thereof.

In the drawings:

Figure 1 is a perspective view of a calculating machine casing embodying my new design;

Fig. 2 is a top plan view of the same; and
Fig. 3 is a rear elevation of the casing shown in Figs. 1 and 2.

I claim:

The ornamental design for a calculating machine casing or similar article as shown.

WALTER D. TEAGUE.
